UNITED STATES PATENT OFFICE.

ERIK AUGUST BOLINDER, OF STOCKHOLM, SWEDEN.

DOVETAILED STAVE FOR BULGED BARRELS AND CASKETS.

Application filed August 21, 1925, Serial No. 51,716, and in Sweden June 14, 1924.

I have filed applications for patent in Sweden June 14, 1924; Germany June 12, 1925; Finland June 9, 1925; Great Britain June 13, 1925; Switzerland June 13, 1925; 5 Spain June 13, 1925; Italy June 13, 1925 and France June 17, 1925.

In making bulged barrels and caskets having dove-tailed staves, a method has been used in which the parts of the joint, that is 10 to say the groove provided in the one edge of the stave and the tongue provided on the opposite edge of the stave have been formed on the lines of circular arcs, so as to permit the parts of the joint of being slid onto 15 each other in the longitudinal direction thereof.

The present invention has for its purpose to provide such a construction of the parts of the joint that their position relatively to 20 the outside and the inside of the stave will be the most suitable with respect to a number of practical points of view.

The arrangement according to the invention is principally characterized by the fact 25 that the parts of the joint extending after circular arcs are disposed in relation to the outside and the inside of the stave in such manner that the parts of the joint are situated, at the central portion of the stave, at a 30 greater distance from the outside of the stave than from the inside thereof. Moreover, the ends of the parts of the joint are at a greater distance from the inside of the stave than is the central portion of the stave.

35 By this arrangement the great advantage is attained that the staves may be produced of the common shape, which experience has shown is the most suitable for bulged barrels and casks, that is to say, the bulge 40 proper may be provided at the central portion of the staves, while the end portions thereof are made straight or nearly straight. the end portions of the cask outside the bulged middle portion will, therefore, be 45 conical or nearly conical in known manner, and the hoops provided about these portions may be driven inwardly onto the cask in known manner, without the tight fit of the hoops on the conical surfaces being altered.

50 By the fact that the parts of the joint are at the central portion of the staves situated at a greater distance from the outside of the stave than from the inside thereof, the portion of the cask which is most subjected to 55 wear in rolling the cask will be reinforced, and by the ends of the parts of the joint be-

ing at a greater distance from the inside of the stave than from the outside thereof, ample material will be obtained for making rigid crozes in the staves. 60

The arrangement is illustrated in the accompanying drawing. Fig. 1 shows a longitudinal section of the stave and Fig. 2 a cross section thereof, on the line *a—a* in Fig. 1. 65

The parts of the joint, that is to say the groove 1 and the tongue 2 are formed on the lines of circular arcs. The distance 3 between the middle points of the parts of the joint and the outside of the stave is 70 appreciably greater than the distance 4 from the inside, and at the ends the distance 5 between the parts of the joint and the inside is greater than the distance 6 from the outside. At the central portion of the stave, 75 a sufficient amount of material will thus remain to withstand outside wear when the cask is rolled, and at the ends there will, likewise, be ample material for making the crozes 7. 80

The edges of the parts 1 and 2 of the joint do not parallel each other, that is to say, they are not mutually concentric, but eccentric, that is to say tapering in a wedge-like fashion toward the one end. This arrangement brings about the special advantage that the parts of the joint may be slid onto each other along the major portion of their length, without appreciable friction or breaking strains being caused thereby, 90 which, on the other hand, will be the case if the edges of the parts parallel one another. Only after the wedge-like parts of the joint have been slid onto each other along the major portion of their length will the resistance be produced which is then overcome by the parts of the joint being forcibly pressed together. By reason of the cross sectional outline of the parts of the joint, the wedge action in the transversal direction 95 of the staves will be powerful enough to pull the staves strongly and tightly onto each other. 100

The eccentric relation between the edges of the parts 1 and 2 of the joint is preferably 105 arranged so that the inner edge of the part is brought with its ends to the same distance from the inside of the stave, while the ends of the outer edge of the part are brought to different distances from the said inside of the stave. This entails the advantage that the material for the crozes 7 will be 110

the same at both ends while also the manufacture will be more easy, in that only one of the cutters used for cutting the groove requires to be movable during work in the direction of the radius of the cut edge.

What I claim as new and desire to secure by Letters Patent of the United States of America is:—

1. A barrel including a plurality of staves 10 having bulged medial portions and substantially straight end portions continuing from the medial portions, the inner surfaces of the end portions of the staves being recessed, jointing means arranged along the edges of

adjacent staves and situated substantially on an imaginary arc of a circle of a greater radii than the barrel staves and positioned in close proximity of the inner surface of the medial portion of the staves and in close proximity to the outer surface of the outer 20 portions of the staves, substantially as and for the purposes set forth.

2. An arrangement as claimed in claim 1, wherein the side edges of the joints taper slightly in wedge-like fashion from one end 25 towards the other.

In testimony whereof I affix my signature.

ERIK AUGUST BOLINDER.
